UNITED STATES PATENT OFFICE.

WILLIAM A. HARTLINE, OF MIDLAND, MICHIGAN.

FOUNTAIN PEN.

Application filed January 30, 1924. Serial No. 689,540.

The present invention relates to fountain pens and particularly to that type known as self filling pens.

The principal object of the invention is to generally improve upon the self filling features thereof so to provide a simple and efficient construction which will be reliable and well adapted to the purpose for which it is designed.

10 With the above and numerous other objects in view as will appear as the description progresses, the invention resides in certain novel features of construction and in the combination and arrangement of parts 15 as will be hereinafter more fully described and claimed.

In the drawing:

Figure 1 is a longitudinal section through the preferred embodiment of my self filling 20 fountain pen,

Figure 2 is a transverse section therethrough taken substantially on the line 2—2 of Figure 1 looking in the direction of the arrow.

25 Referring to the drawing in detail, it will be seen that the preferred embodiment of my fountain pen includes a barrel 1 and a casing 2, the casing 2 being threadedly mounted on the barrel 1 as at 3 so as to be disposed in 30 longitudinal alignment therewith. The end 4 of the barrel 1 is provided with an opening in which the end 5 of the collapsible sack 6 extends and is secured. Compression means for this sack 6 is provided in conjunction 35 with the casing 2 and consists of an elongated loop member 7 terminating in a pindle 8 to which is hinged an arm 9. The normal position of this arm is shown in Figure 1 and it will be readily understood that it 40 may be swung to the dotted line position in Figure 1 and then moved or swung so as to rotate the pindle 8 and also the loop 7 so as to cause said loop to compress the collapsible sack 6. When the arm 9 is re-

leased this collapsible sack will return to its 45 normal position so as to draw ink into the reservoir of barrel 1. The collapsible sack 6 is so constructed and arranged that it will only draw in enough ink to fill the reservoir in the barrel 1 and the sack itself is not 50 adapted to be filled. Thus, the sack is not designed for holding ink but simply serves as a means for drawing the ink into the reservoir of the barrel. The fact that the sack is not continuously filled with ink 55 serves to retain the same in a good condition for a considerable length of time and the sack is therefore not subjected to the deteriorating effects of the ink so that it is not liable to become quickly rotted. 60

Although I have described my invention with a certain degree of particularity, it is to be understood that numerous changes in the details of construction, and in the combination and arrangement of parts may be 65 resorted to without departing from the spirit or scope of the invention as herein-after claimed.

Having thus described my invention, what I claim as new is:

In a self filling fountain pen, a casing, a collapsible sack arranged within the casing, a compressing means associated with the collapsible sack, comprising an elongated loop disposed in the casing beside the 75 collapsible sack and terminating at one side of its outer end in a longitudinal pindle journaled through the outer end of the casing, and an arm hinged to said pindle whereby it may be rotated for swinging the 80 elongated loop to compress the collapsible sack, said arm normally overlying the end of the casing and being movable to a position wherein the same projects laterally outwardly beyond a side of the casing for facilitating its actuation.

In testimony whereof I affix my signature.

WILLIAM A. HARTLINE.
